J. ADDISON CROWELL, OF WALLKILL, NEW YORK, ASSIGNOR TO JAMES B. CROWELL & SON, OF WALLKILL, NEW YORK, A CORPORATION OF NEW YORK

BRICK MOLD

Application filed January 24, 1929. Serial No. 334,672

The present invention relates to molds, and more particularly to a novel and improved mold for use in the manufacture of brick by the "soft mud process," wherein the clay material is forced through a die into a set of molds, the present invention being an improvement on the mold illustrated, described and claimed in my prior and copending application Serial Number 313,332, filed October 18, 1928.

10 An important feature of the present invention is the provision of means to strengthen, reinforce, and add to the wear of brick molds. Broadly considered, this feature 15 consists in the application to a brick mold, and particularly along the bottom thereof, of a metallic reinforcing strap of considerable thickness. Said strap is preferably laid in a dado running longitudinally of 20 the backs or panels of a brick mold so that the reinforcing strap will be flush with the bottom panels of said mold. The preferred position of said strap is along the central bottom of the mold, and I preferably utilize 25 but a single strap, although it will be appreciated that I may vary this by utilizing more than one strap if desired and suitably spacing said straps one from the other.

This metallic reinforcing and strengthening strap will take up the strains when my novel molds are utilized in automatic brick machines, or hand operations of "beating" or "bumping" the bottoms of the mold to knock out the formed clay.

35 A further object of the invention resides in the fastening or securing of said strap to each back or panel in such a manner as to not interfere with the swelling and contraction of the wood of which the backs are formed.

40 Another and important feature of the present invention resides in so constructing my novel mold that the partitions will not rest on or be supported by the mold bottoms or panels. This is an important feature, as it
45 will relieve the panels of considerable of the strain and wear to which they have been heretofore subjected, and will substantially eliminate all likelihood of splitting of said panels due to the jars, blows, hammerings or bumpings to which the molds are subjected.

Another feature of the invention resides in so constructing the panels of my novel mold that they are of the same width as the width of each individual mold, thus bringing the edges of the panels at the sides up to but not under the partitions. 55

A still further and important feature of the invention resides in positioning, between each pair of panels, a block, preferably slightly scant of the space provided between said panels, this block being preferably of wood, and preferably also of less length and width than the length and width of the partitions. These blocks will extend flush with the bottoms of the panels and will be dadoed to receive said reinforcing straps, which may or may not be secured to said blocks. 60 65

These blocks, positioned between the panels may be separate from the partitions and secured thereto in any desirable way, or they may be an integral part of the partition but, when made an integral part of the partition, will still be of less length and width than the length and width of the partitions. 70

By constructing these blocks slightly scant of the space between panels, ample provision is made for swelling, or "give and take" of the wood of the panels during the alternate wettings and dryings to which they are subjected. 75

By thus bringing the partitions into contact with the reinforcing strap on the mold bottom, either through the medium of the separate blocks or the blocks when formed integral with the partitions, considerable of the strains and stresses will be taken up by the partitions themselves, thus reducing the strain and wear on the panels and still further lessening the likelihood of splitting of the said panels.

A brick mold constructed according to the above brief description, will successfully withstand the bumpings and jars of any soft mud brick machine.

A further feature of the invention, and one by which the mold is considerably strengthened and reinforced, consists in providing, on each upper surface of the thickened ends of the mold, a metallic plate, and in extending the reinforcing strap up over the ends of the 100

mold and under said plates, dadoing or mortising said strap into the blocks at the ends of the mold so that the said metallic plates may seat flush on said ends.

A still further feature of the invention resides in providing, in the bottom panels, a plurality of cut-out portions, preferably on each side adjacent to each corner. Thus when the mold is assembled, the normal sides or edges of the panel will be flush with the bottom edges of the partitions, and the cut-out portions referred to will insure ample vent openings. These openings, furthermore, are flared downwardly, thus insuring against clogging of the vents. This mold, therefore, will produce no "fins" or feathers on the brick constructed therein, these vents permitting the air to be forced out of the mold as the clay is forced in, and will permit the clay, in its plastic state, to flow fully into and completely fill the mold, particularly at the ends, corners and sides of the bottom. Furthermore, when the molds are inverted to "dump" the brick therefrom, these vents will permit the entrance of air therethrough to facilitate in releasing the grip of the brick in the molds.

My novel mold is strong, durable and rugged, and enables the use of relatively stiff clay therein, the resulting brick made from said stiff clay standing up better, drying quicker, and burning more uniformly, thus improving the entire manufacture of the brick from pug mill to kiln.

Furthermore, my novel mold prevents deformation of the brick manufactured therein, and said mold, because of its strong and rugged construction, will stand up in service better and longer than previous molds, thus resulting in an economy to brick manufacturers, as prior brick molds must be frequently replaced, due to the harsh treatment they receive during the processes of brick manufacture. The mold of the present invention is especially constructed to withstand this harsh treatment, and to stand up under the blows, jars, bumps, shocks and hammerings received, for a considerable period of time without repair or replacement.

I believe that the mold of the present application, above described, is novel, and I have therefore claimed the same broadly in the present application.

The above and other features of the invention, details of construction, combinations of parts and advantages, will be hereinafter more fully pointed out, described and claimed.

Referring to the drawings, illustrating preferred embodiments of the present invention,

Fig. 1 is a top plan view of the preferred form of mold;

Fig. 2 is a side elevation of the mold illustrated in Fig. 1;

Fig. 3 is a fragmentary bottom plan view of the mold of Figs. 1 and 2;

Fig. 4 is a fragmentary longitudinal sectional view on the line 4—4 of Fig. 1;

Fig. 5 is a cross-sectional view, partly broken away, on the line 5—5 of Fig. 3;

Fig. 6 is a perspective view of one of the bottom panels, illustrating the cut-outs for the vents and the dado for the reinforcing strap;

Fig. 7 is a perspective view of one of the blocks interposed between the bottom panels, when utilized as a separate unit;

Fig. 8 is a perspective view of the partition and block as a unit;

Fig. 9 is a fragmentary top plan view of my invention of reinforcing strap applied to a modified type of mold;

Fig. 10 is a side elevation of the mold of Fig. 9;

Fig. 11 is a cross-sectional view on the line 11—11 of Fig. 9;

Fig. 12 is a fragmentary top plan view, partly broken away, of a further modified mold;

Fig. 13 is a side elevation of the mold illustrated in Fig. 13;

Fig. 14 is a cross-sectional view on the line 14—14 of Fig. 12;

Fig. 15 is a fragmentary top plan view of a still further modified type of mold with my novel reinforcing and strengthening strap applied thereto; and

Fig. 16 is a side elevation, partly broken away, of the mold illustrated in Fig. 15.

It will be appreciated that the brick molds carrying out my invention may be of any suitable or desired size or number of brick. The invention may be embodied equally in a hand sized mold for forming one, two or more brick for hand dumping, handling and use, or in the present molds of six, seven, eight brick or more, for use in the modern high speed or automatic brick machines and presses.

Referring now to the drawings, for a particular description of my invention, I have illustrated a seven brick mold, this being for illustrative purposes only, as will be readily understood. The mold illustrated is of the type utilized in the modern high speed or so-called automatic brick making machines, said mold comprising the end blocks 1 and 2, sides 3, 3, partitions 4, 4, and bottom or back panels 5, 5. These portions are constructed of wood, and are dovetailed together, fastened in various ways and usually bound with iron bands 6, 6.

Beneath each partition 4 is positioned a block 7, preferably also of wood, said blocks, as clearly illustrated in Fig. 3, being of less length and width than the partitions 4. The blocks 7 may be constructed as separate units, as illustrated in Fig. 7, in which instance they would be preferably provided with apertures

8, 8, through which screws 9 or other retaining devices may be inserted to secure the blocks 7 to the bottoms of the partitions 4. These blocks 7 are preferably on the same plane as the bottoms of the panels 5, and as illustrated in Fig. 3, one block is positioned between each pair of panels 5, being normally preferably scant of the space between said panels 5.

10 Each of the panels 5 is provided with a dado 10, and each of the blocks 7 is provided with a dado 11 alined with the dadoes 10.

These dadoes are preferably in the middle of each panel and block, and form a more or less continuous groove or dado longitudinally of the center of the bottom of the mold. Laid in this dado and extending longitudinally of the bottom of the mold, is a relatively thick and heavy metallic reinforcing and strength-20 ening strap or bar 12, secured to the panels 5 by screws 13 or the like, and which may be secured to the blocks 7 by screws 14, if desired, although this is not essential.

The dadoes 10 and 11 are of a sufficient depth so that when the strap 12 is laid therein said strap will be flush with the bottoms of the panels 5 and blocks 7. In the preferred form of the invention the strap 12 is continued over the ends of the mold, being 25 dadoed in the end blocks 1 and 2 and extending over the tops of the blocks 1 and 2, where it is also dadoed, as illustrated in Fig. 4. A metallic plate 15 is secured over the end blocks 1 and 2 and the end partition 4, and each end 30 of the strap 12 is concealed under and protected by said plates 15, thus firmly anchoring said strap in place and eliminating any roughness, corners or edges due to exposed ends of the strap 12.

40 The construction of my mold with this reinforcing strap 12 results in a rugged durable mold, one possessed of great strength and wearability, and which will withstand the blows, "beatings" and hammerings to 45 which such molds are subjected, the strap 12 receiving much of the wear and strains which have been hitherto imparted to and borne by the wood of the panels of the mold.

The top of each partition 4 is also preferably provided with a metallic strap 16 suitably secured to said partitions, as by screws 17.

If desired, rather than utilizing separate blocks 7, as illustrated in Fig. 7, I may form the partitions 4 with integral depending portions 18 which would be of less length and width than the partitions 4, and which portions 18 would be provided with a dado 19 similar to the dado 11 in the block 7, the portions 18 performing the same functions as do the blocks 7.

In the preferred form of brick mold, the panels 5 are of the same width as the width of each individual brick mold, so that the edges 20 of said panels will normally be

aligned with the bottom edges 21 of the partitions 4 as clearly illustrated at 22 in Fig. 4.

The blocks 7 being scant of the space between each pair of panels 5, will allow ample "give and take" of the wood as the same is alternately wet and dried.

The fact that the edges of the panels 5 do not normally project under the bottoms of the partitions 4 will also allow sufficient "spring" in said panels, when subjected to 75 blows or "beatings", to insure against splitting of the said panels, a difficulty and condition which has been prevalent with prior types of brick molds. Also, the fact that the partitions 4, either directly or through the medium of the blocks 7, are in contact with the strap 12, will permit said partitions to absorb a portion of the strains and blows imparted to the bottom of the mold, and thus relieve the panels to that extent.

In the panels 5 and at the edges thereof, I provide a plurality of recesses 23, preferably beveled or flared outwardly or downwardly, the same being also in balanced relation, and of suitable length to cooperate with the bottom edges of the partitions 4, when assembled, to afford a full vent effect with its consequent advantages and benefits in the resulting brick.

It will be appreciated that I am not limited to the number of recesses 23 illustrated, but may provide the panels 5 with any desired number thereof, commensurate with the qualities and characteristics of the clays utilized. Also, the size or proportions of the recesses 23 may be suitably varied for different types of clays. By the use of these vents, the clay is enabled to fully enter all parts of the mold, the vents permitting the discharge of air from the edges and corners of said molds, and said vents also cooperating to facilitate the dumping of the bricks from the mold, by permitting the entrance of air through the vents to the bottoms of the brick as they are dumped.

In Figs. 9, 10 and 11, I have illustrated my feature of reinforcing and strengthening strap applied to a modified type of mold, wherein the panels 26 are free of contact with the partitions 27, thus providing slots or vents 28 extending the full length of each individual mold section. In this form of mold there is no connection or contact between the partitions 27 and the strap 29, said strap being laid in dadoes 30 formed in the central bottom of each panel 26. The ends of the strap 29 are brought up over the ends of this mold and concealed under and protected by a metal plate 31, similar to the plate 15.

In Figs. 12, 13 and 14, I have illustrated the feature of the reinforcing strap applied to a still further modified type of mold, wherein the partitions 32 rest directly on panels 33, separate panels 34 being provided

covering the major portion of the bottom of each individual and being spaced from the panels 33, whereby slots or vents 35 are provided, spaced from the partitions 32 and 5 extending the full length of each individual mold.

The reinforcing and strengthening strap 36 is dadoed in grooves 37 in each panel 33 and 34, and said strap extending over the 10 ends of the mold and being concealed under and protected by metallic plates 38 covering the end blocks 39 and 40 and end partition 32.

In Figs. 15 and 16 I have illustrated a still 15 further modification of mold having my invention of reinforcing and strengthening strap applied thereto. In this type of mold the edges of the panels 41 extend under the partitions 42 while still leaving space or 20 clearance between the adjacent sides of said panels to allow for "give and take". Each panel 41 is provided with vents or slots 43. Dadoed in the bottom of each panel 41 is a 25 reinforcing and strengthening strap 44, the ends of which are brought up over the ends of the mold, being dadoed therein, and being concealed under and protected by a metallic plate 45 which covers the end block 46, this 30 end block also functioning as partition for the end brick mold.

The features, advantages, utility and efficiency of my novel molds will instantly appeal to those skilled in the art, and because of their rugged, strong construction, particularly the reinforcing strap or straps, will give efficient and long service without need for repair or replacement.

While I have necessarily described my present invention somewhat in detail, it will 40 be appreciated that I am not limited thereto, but may vary the size, shape and arrangement of parts within reasonably wide limits without departing from the spirit of the invention.

45 It will also be appreciated that instead of utilizing one central longitudinal reinforcing strap, similar to the strap 12, I may utilize more than one of said straps, if desired, suitably spacing the same one from the other, but I find that the single central reinforcing strap functions very efficiently and results in a very rugged, durable mold.

50 My invention is further described and defined in the form of claims as follows:

55 1. In a brick mold, a plurality of bottom panels, a plurality of partitions, a block of less length and width than said partitions positioned between each pair of panels, each of said panels and blocks having a dado intermediate their ends, and a metallic reinforcing strap in said dadoes, flush with the bottoms of said panels and blocks and extending longitudinally of said mold.

60 2. In a brick mold, a plurality of bottom panels, a plurality of partitions, a block of

less length and width than said partitions positioned between each pair of panels and scant of the space between said panels, each of said panels and blocks having a dado intermediate their ends, and a metallic reinforcing strap in said dadoes, flush with the bottoms of said panels and blocks and extending longitudinally of said mold. 70

3. In a brick mold, a plurality of bottom panels, a plurality of partitions, a block of less length and width than said partitions positioned between each pair of panels, the upper side edges of said panels being normally flush with the bottom edges of said partitions, each of said panels and blocks having a dado intermediate its ends, and a metallic reinforcing strap in said dadoes, flush with the bottoms of said panels and blocks and extending longitudinally of said mold. 75

4. In a brick mold, a plurality of bottom panels, a plurality of partitions, and a block of less length and width than said partitions positioned between each pair of panels. 80

5. In a brick mold, a plurality of bottom panels, a plurality of partitions, and a block of less length and width than said partitions positioned between each pair of panels and scant of the space between said panels. 85

6. In a brick mold, a plurality of bottom panels, a plurality of partitions, a block of less length and width than said partitions positioned between each pair of panels, each of said panels and blocks having a dado intermediate its ends, a reinforcing strap in said dadoes flush with the bottoms of said panels and blocks, and a metallic plate at each end of the top of said mold, said strap extending over the ends of said mold and the ends of said strap being concealed under and protected by said plates. 90

7. In a brick mold, a plurality of bottom panels, a plurality of partitions, a block of less length and width than said partitions positioned between each pair of panels and scant of the space therebetween, each of said panels and blocks having a dado intermediate its ends, a reinforcing strap in said dadoes flush with the bottoms of said panels and blocks, and a metallic plate at each end of the top of said mold, said strap extending over the ends of said mold and the ends of said strap being concealed under and protected by said plates. 100

8. In a brick mold, a plurality of bottom panels, a plurality of partitions, certain of said partitions having a depending portion of less length and width than said partition, each of said depending portions being positioned between a pair of panels. 110

9. In a brick mold, a plurality of bottom panels, a plurality of partitions, certain of said partitions having a depending portion of less length and width than said partition, each of said depending portions being positioned 115

between a pair of panels and scant of the space therebetween.

10. In a brick mold, a plurality of bottom panels, a plurality of partitions, certain of said partitions having a depending portion of less length and width than said partition, each of said depending portions being positioned between a pair of panels, the upper side edges of said panels being normally flush with the normal bottom edges of said partitions.

11. In a brick mold, a plurality of bottom panels, a plurality of partitions, certain of said partitions having a depending portion of less length and width than said partition, each of said depending portions being positioned between a pair of panels and scant of the space therebetween, the upper side edges of said panels being normally flush with the normal bottom edges of said partitions.

20. In testimony whereof, I have signed my name to this specification.

J. ADDISON CROWELL.
